UNITED STATES PATENT OFFICE.

JOHN ROSQUIST, OF PARK CITY, UTAH TERRITORY.

CAR FOR INCLINES IN MINES..

SPECIFICATION forming part of Letters Patent No. 292,366, dated January 22, 1884.

Application filed August 31, 1883. (No model.)

To all whom it may concern:

Be it known that I, JOHN ROSQUIST, of Park City, in the county of Summit, Utah Territory, have invented a new and useful Improvement 5 in Cars for Inclines in Mines, of which the following is a full, clear, and exact description.

This invention consists in a novel self-acting pawl attachment to cars for inclined planes in 10 mines, whereby on the rope or other appliance which controls the raising and lowering of the car giving way the pawl or pawls are made to automatically engage with a locking rack or racks on the track, to stop the car at any point 15 thereon, thus making the car a safety one.

Reference is to be had to the accompanying drawings, forming a part of this specification, in which similar letters of reference indicate corresponding parts in all the figures.

20 Figure 1 represents a central vertical longitudinal section of a mine-car in part, and inclined track on which the same runs, with my improvement applied, and showing the safety-attachment as out of action during the ordinary 25 travel of the car. Fig. 2 is a plan of the same, with the parts in like position; and Fig. 3, a vertical longitudinal section in part, showing the car as stopped by its automatic safety-attachment.

30 A is the frame of the car, on which the usual box is arranged, and which runs by its wheels b b on the rails B B of an inclined track, such as is usual in mines. Secured to the track, between the rails B B and parallel with them, 35 are a pair of locking-racks, C C, formed with hook-shaped teeth arranged with their locking-faces toward the summit of the incline, and set slightly inclining backward in a downward direction. These racks run the whole length 40 of the inclined track, or thereabout.

D D are hooks or pawls fastened at their inner ends to a cross-beam or shaft, E, having its bearings in or near the front ends of the sides of the frame A, and being free to turn or rock therein.

45 F F are springs attached at their one end to the frame of the car or to one of its stationary axles, and coiled around and secured at their opposite end to the rocking beam or shaft E, 50 in such manner that said springs will have a normal tendency to so turn said beam or shaft

as that the pawls D D will be thrown down into engagement with the locking-rack C C. They are held out of engagement with the racks, when the car is being run down or drawn up 55 the incline, as shown in Fig. 1, by the shaft attachments or connections which unite the car with the rope or other appliance used to raise and lower it—as, for instance, by a rod, chain, or rope, d—attached at its inner end to 60 a short tongue, e, secured to the rocking-beam E at an angle, when the pull is on it, to so turn the beam E against the action of the springs F F as to keep the pawls D D free from engagement with the racks C C, which connection, d, as also other draft-connections, f f, 65 connected directly with the frame of the car, unite at their outer ends with the rope or other appliance used to raise and lower the car. In this way or by these means whenever the rope or other appliance used to raise 70 and lower the car breaks or gives way the springs F F will so turn the beam E as to throw the pawls D D into engagement with the racks C C, as shown in Fig. 3, thus automatically 75 stopping the car at any point in the length of the incline.

I have here described duplicate racks C C, pawls D D, and springs F F, but do not restrict myself to any number of these, one or 80 more of each being used as desired.

Having thus fully described my invention, I claim as new and desire to secure by Letters Patent—

1. In cars for ascending and descending inclines in mines, the combination, with the car, its inclined track, and one or more locking-racks on said track, of an automatic pawl attachment to the car, connected with and controlled by the rope or appliance by which the 90 car is raised or lowered, substantially as specified, and whereby in case of said rope or appliance giving way the car will be stopped at any portion of or different points in the length of the track, as herein set forth.

2. In cars for ascending and descending inclines in mines, the combination, with the draft devices or connections between the car and the rope or appliance by which the car is raised or lowered, and with one or more locking-racks on the car-track, of a rocking beam or shaft carried by the car, and connected with

the draft-devices, one or more pawls controlled by said beam, and means for throwing the pawl or pawls into engagement with the rack or racks upon the car being liberated from the 5 rope or appliance by which it is raised or lowered, essentially as described.

3. The combination of the car A, the rails B B of the inclined track, one or more locking-racks, C, on said track, the rocking beam 10 or shaft E, one or more pawls, D, carried by said shaft, a spring or springs, F, for rock-

ing the shaft to throw the pawl or pawls into engagement with the rack or racks, and the tongue e and draft-connection d, for holding the pawl or pawls out of lock with the rack or 15 racks, essentially as and for the purposes herein set forth.

JOHN ROSQUIST.
